poration of Illinois

Application August 9, 1945, Serial No. 609,789

9 Claims. (Cl. 251—163)

1

The present invention relates to gas valves and more particularly to the provision of gas valves with new and improved valve positioning and indicating means.

The primary object of the present invention is to provide a new and improved gas valve positioning and indicating mechanism which is simple and compact in construction, and, more specifically, sufficiently compact so that it may be readily utilized with valves having threaded or bayonet lock type top caps.

Another of the primary objects of the present invention is the provision of a new and improved positioning and indicating mechanism for a plural position gas valve, and especially a mechanism for indicating high and low positions of a valve of the type commonly called a high-low valve.

A further object of the present invention is the provision of a new and improved valve positioning and indicating mechanism capable of producing an audible indication when the valve is substantially in its full on position.

Another object of the present invention is the provision of a new and improved positioning and indicating mechanism for a high-low valve capable of producing an audible indication, such as a click, when the valve is in a position supplying sufficient gas for ignition, and producing resistance to movement when the valve is in another operating position, i. e., the low position.

A further and more specific object of the present invention is to provide a new and improved valve positioning and indicating mechanism including a pair of discs or plates rotatable with the valve or valve stem and one of which is only frictionally connected to the valve stem for movement with it, whereby the two plates are angularly movable with respect to each other, and said one plate being movable longitudinally of the stem to provide an audible indication of one valve position and also restraining angular movement of the other plate to determine and indicate the other valve position.

Other objects and advantages of the present invention will become apparent from the ensuing description of an embodiment thereof, in the course of which reference is had to the accompanying drawings, in which:

Fig. 1 is an axial cross-sectional view through a valve including the positioning and indicating mechanism of the present invention, the usual valve operating handle being omitted for the sake of simplicity;

Fig. 2 is an exploded view of a portion of the valve illustrated in Fig. 1, showing the various parts and construction of the novel positioning

2

and indicating mechanism of the invention. The parts are illustrated in the positions occupied by them when the valve is in its off position;

Fig. 3 is a fragmentary cross sectional view taken along the line 3—3 of Fig. 1. The valve is in an intermediate, the low position, in both of these figures;

Fig. 4 is a view similar to Fig. 3, with the valve in its off position;

Fig. 5 is a view similar to Figs. 3 and 4, with the valve in a position just prior to the production of an audible indication that sufficient gas is being supplied for good ignition;

Fig. 6 is a view similar to Figs. 3, 4, and 5, with the valve in a position whereat the audible indication is produced.

Fig. 7 is a view similar to Figs. 3 to 6 with the valve in its full on position;

Fig. 8 is a view similar to Fig. 1 of another embodiment of the invention utilizing two discs or plates instead of the three utilized in the previous embodiment;

Fig. 9 is an exploded view of the embodiment of the invention illustrated in Fig. 8;

Fig. 10 is a fragmentary cross sectional view taken along the line 10—10 of Fig. 8; the valve being shown in an intermediate, the low position, in both of these figures; and

Figs. 11, 12, 13 and 14 are views similar to Fig. 3, illustrating the valve in its off position, a position just prior to the production of an audible click indicating that sufficient gas is being supplied for good ignition, a position whereat an audible indication is produced, and the full on position, respectively.

The present invention has been illustrated in conjunction with a plural position gas valve 10 of the type commonly called high-low valve. The valve includes a rotatable tapered valve plug 12 movable from an off position, wherein no gas flows through the valve, to high and low positions wherein different quantities of gas flow to the burner, and to an intermediate position substantially at the full on position whereat an audible indication is given of the passage of sufficient gas for good ignition. In the high position, a larger quantity of gas flows to the burner and in the low position a smaller quantity of gas flows to the burner. The valve includes a body 14 within which the plug is rotatably mounted in conventional manner.

Gas is supplied to the valve from a suitable source of gas (not shown) through a manifold 16 and regulated quantities of gas are supplied to a burner, not shown, which is connected to the outlet of the valve through a mixing tube 18, which may be of conventional construction. The

gas valve includes also an outlet passageway 20 communicating with an outlet chamber 22 from which gas flows into the mixing tube through a hood 24 having a discharge orifice 26. The hood is adjustable in order that the effective area of the orifice may be varied.

The valve includes an inlet passageway 30 providing communication from the manifold to a tapered bore or passageway 32 within the valve body in which the tapered inner portion 34 of the valve plug is rotatably mounted. The plug has an outlet passageway 36 located coaxially of the plug and opening at its outer end to the chamber 22.

As heretofore indicated, the valve is of the plural position type. In one angular position of the plug, a larger quantity of gas is supplied to the valve and in another (the low position) a smaller quantity. In the former of the two positions, the inlet and outlet passageways 30 and 36, respectively, are interconnected through a relatively large sized radial passageway 38 extending from the exterior surface of the valve plug to the axial passageway 36. In the illustrated valve, sufficient gas for good ignition flows through the valve at a valve position somewhat short of the full on position, i. e., shortly before the passageways 30 and 38 are fully aligned. In the low position, a preadjusted smaller quantity of gas flows to the axial passageway from the inlet passageway through a two-part passageway 40 extending generally radially through the valve plug and an auxiliary adjustable low adjustment valve 42 having an axial passageway 44 communicating with the passageway 36 in the valve plug and a radial passageway 46 connecting the passageways 40 and 44.

The auxiliary adjustable valve is movably mounted in gas-tight manner within an intermediate passageway 48 in the valve plug, and is provided with a slot 50 at its outer end whereby it may be rotated to adjust the effective size of the orifice formed by the passageways 40 and 46 in the plug and auxiliary valve, respectively. The slot 50 is accessible through an axial passageway 52 in the valve stem 54, which, in the instant embodiment, is an integral part of the valve plug. The adjustment of the quantity of gas flowing in the low position may easily be effected after the usual valve handle, not shown, has been detached from the stem. The stem or low adjustment illustrated and described immediately above forms no part of the present invention, it being disclosed and claimed in the copending application of Philip S. Harper, Serial No. 576,673, filed February 7, 1945, and assigned to the assignee of this application.

The novel positioning and indicating mechanism of the present invention is housed within a top cap 60 detachably secured to the valve body. It is preferable, but not necessary, that the top cap be detachably secured by a bayonet lock type connection. The top cap is generally cup-shaped and has a central aperture 62 through which the valve stem 54 passes freely. The cap has a pair of diametrically opposite inwardly extending lugs 64 cooperating with generally J-shaped passageways 66 on the exterior of the valve body to provide the bayonet lock type detachable connection.

Referring particularly to Fig. 2, it may be noted that the top cap may be secured to the valve body by passing it along the valve stem 54 and valve body on to the slots 66, after which it can be locked on the body by moving it angularly

until the lugs 64 are opposite the shorter ends 68 of the J-shaped slot 66 whereat the cap is moved outwardly and thus securely held by a short helical spring 70 surrounding the valve stem. One end of the spring bears against a shoulder 72 at the larger diameter end of the tapered portion 34 of the valve plug and the other exerts an outward force upon the top cap through a plurality of discs or plates 80, 82, and 84 comprising the novel positioning and indicating mechanism of the present invention. If desired plates 80 and 84 may be combined in a single plate, as described in the embodiment of the invention disclosed Figs. 8 to 13, inclusive.

The positioning and indicating mechanism of the present invention may be constructed simply and economically, and may be readily housed within a portion of the valve body and the top cap. It is preferred that the mechanism determine and indicate a plurality of positions of the valve. In the instant embodiment of the invention the mechanism produces an audible indication or click when the gas valve is operated to a position whereat sufficient gas for ignition is supplied to the burner, and another, the low position is indicated by restraint of movement of the valve. Two other positions, the off and full on positions, are determined and indicated by positive restraint of movement of the valve.

The novel mechanism includes a pair of discs or detent plates, one of which is constrained for movement with the valve plug and preferably the valve stem, and the other of which is frictionally movable with the stem through a predetermined angular distance, after which it is prevented from moving and the other plate moves angularly with respect to it. After such relative movement has occurred for a predetermined distance in one direction, the frictional plate moves toward and engages the other so as to produce an audible sound, and when the relative movement is in the opposite direction, the frictional plate restrains but does not prevent movement of the other plate.

Returning again to the drawings, it may be noted that the valve body is provided with a longitudinally extending arcuate projection 85, the shoulders 86 and 88 of which are spaced apart a predetermined distance to determine the extent of angular movement of the valve. In the illustrated embodiment of the invention, the shoulders are spaced apart a distance of substantially 180°. The extension 85 is radially spaced from the stem outwardly a sufficient distance to accommodate at least the plates 80 and 82 which have radial extensions 90 and 92, respectively, cooperatively associated with the shoulders 86 and 88, as will become more apparent shortly. The plates 80 and 84 are constrained to rotate with the valve, preferably, by providing them with generally D-shaped apertures, the flats 94 and 96 of which, respectively, engage a corresponding flat 98 on the valve stem 54. The outer end of the valve stem is flattened as indicated by reference character 100 non-rotatably to receive a valve operating handle, not shown.

The off and full on positions of the valve are determined by the washer 80, which is constrained to move with the valve and valve stem. These positions are determined and indicated by the engagement of the extension 90 of the plate with the shoulders 86 and 88, respectively. The off position is indicated in Fig. 4, from which it may be noted that the extension 90 is in engagement with shoulder 86. The full on position is shown

in Fig. 7, from which it may be noted that extension 90 is in engagement with the other shoulder 88.

The two plates 82 and 84 are provided with a plurality, preferably at least three, of axial projections maintaining the two plates in spaced relation under certain conditions and impositively restraining movement of one plate relative to the other under other conditions. The projections in plate 82 are indicated by the reference character 102 and those in the plate 84 by reference character 104. The projections may be of various constructions, but it is preferred that they be substantially V-shaped radial grooves stamped or otherwise formed in the plates. In the illustrated embodiment, the grooves are spaced about 120° apart.

An audible indication is produced by the sudden movement of plate 82 axially outwardly into substantially full engagement with the plate 84. The spring 70 urges plate 82, and when the projections 102 approach alignment with projections 104, plate 82 is moved suddenly by the spring to engage plate 84, thereby to produce the audible indication. This audible indication is produced, as heretofore indicated, when the valve plug 12 is turned to a position whereat the burner is supplied with sufficient gas for good ignition. Preferably, this position is close to the full on position.

In the off position of the valve, illustrated in Fig. 4, it may be noted that the plate 82 is maintained out of substantial engagement with plate 84 by the projections 104 which are out of alignment with the projections 102. In this position the radial extensions 90 and 92 of the stop and frictional plates 80 and 82 are both in engagement with shoulder 86. When the valve stem is moved counterclockwise, as viewed in Fig. 4, to the position illustrated in Fig. 5, the three plates move as a unit. Plates 80 and 84 are constrained positively to move with the valve stem while plate 82 moves in unison with the others because it is frictionally held between them. This unitary movement occurs until the radial extension 92 in plate 82 strikes the shoulder 88, as illustrated in Fig. 5. Further counterclockwise movement of the valve now results only in the movement of plates 80 and 84, with the result that projections 102 and 104 in plates 82 and 84 approach alignment and the spring 70 finally and suddenly moves plate 82 outwardly along the stem to bring the projections 102 and 104 into what may be considered a nesting position, as illustrated in Fig. 6.

In order that the movement of the plate 82 may be sudden so as to provide a distinct indication, the friction between plates 80 and 82 is such that the plate 82 may move not only longitudinally, but return a short distance in a clockwise direction so that the radial extension moves out of contact with the shoulder 88 to the position shown in Fig. 6, where it is substantially the same distance from the shoulder 88 as radial extension 90 in the stop plate. The reduction in friction between plates 80 and 82, it may be noted, is provided by projections 102 in the frictional plate 82 reducing the area of contact.

After the burner has ignited, the valve may be turned to the full on position or to a low position. Movement of the valve to the full on position is accomplished by rotating the valve further in a counterclockwise direction to the position illustrated in Fig. 7. In this position, both radial extensions 90 and 92 are in engagement

with the shoulder 88, all three of the plates moving as a unit during this further counterclockwise movement.

To operate the valve to its low position from either the ignition or full on positions, the valve plug is rotated in a clockwise direction. During such movement the three plates move as a unit with the valve stem. Plates 80 and 84 are constrained positively to move with the valve while the plate 82 is impositively constrained so to move because of the nested relationship between the plates 82 and 84.

The low position is determined and indicated by impositive constraint of further movement in a clockwise direction. This constraint occurs when the extension 92 of friction plate 82 engages shoulder 86 as illustrated in Fig. 3 (see also Fig. 1).

To move the valve to its off position, the plug is moved further in a clockwise direction from the position in which it is shown in Fig. 3 to the position in which it is shown in Figs. 2 and 4. This further movement can be accomplished only by the exertion of sufficient force to cam plate 82 axially inwardly and away from plate 84. When the valve plug is turned, plate 82 is prevented from turning by the engagement between extension 92 and shoulder 86 while plate 84 turns with the valve stem. After the plates have been cammed apart, the projections 104 of plate 84 ride on the surface of plate 92 until extension 90 of the stop plate also engages the shoulder 86, as illustrated in Fig. 4.

It should be understood that various modifications of the above described embodiment may be made. For instance, the angular extents of the radial projections 90 and 92 may be varied as may be the angular distance between the shoulders 86 and 88. The particular construction of the projections in the plates 82 and 84 may also be varied.

The embodiment of the invention illustrated in Figs. 8 to 14, inclusive, is in many respects like that described above and like parts have been indicated by like reference characters. It includes a top cap 60 differing somewhat from that of the previously described embodiment, it having an indented central portion. In this embodiment of the invention, however, only two discs are utilized, these being the disc 82 and a second disc 110 combining the functions of discs 80 and 84 of the previously described embodiment. In other words, the disc 110 performs the function of the positioning and indicating disc and also the functions of the disc 80 in determining the full on and off positions of the valve.

The disc 110 is located inwardly of the disc 82, as may be best noted from Figs. 8 and 9. It has a flat 112 constraining it for rotation with the valve and valve stem. It also has a short radial extension 114 cooperatively associated with the shoulders 86 and 88 on the valve body for indicating the full on and off positions by positive restraint to further movement of the valve and valve stem. It includes also a plurality of projections 116 cooperatively associated with the projections 102 of the disc 82.

It is believed that the operation of the embodiment of the invention illustrated in Figs. 8 to 13 will be apparent from the foregoing brief description of the detailed construction, but it will be reviewed briefly.

The off and full on positions of the valve are determined by the disc 110, and more particularly, the radial extension 114 thereof, which en-

gages the shoulders 86 and 88. The off position is illustrated in Fig. 11. In this position, the radial extension 114 abuts against the shoulder 86 thereby limiting clockwise movement of the valve. The full on position is illustrated in Fig. 14, in which the radial extension 114 is in engagement with the shoulder 88, thereby positively restraining counter-clockwise movement of the valve. It may be noted also that in the off position, the projections 102 and 116 in the discs 82 and 110, respectively, are out of alignment, but that they are in alignment in the full on position. It may be noted further that the radial extension 92 of the disc 82 abuts against the shoulders 86 and 88 in the off and full on positions, respectively.

When the valve is turned from its off position toward the full on position, the detent disc 110 is positively turned with the valve while the detent disc 82 is moved because of its frictional engagement with the other disc. The two discs rotate simultaneously until the radial extension 92 in the disc 82 strikes the shoulder 88 (see Fig. 12), after which the disc 110 alone turns with the valve. As a result, the projections 116 in the disc 110 approach the projections 102 in the disc 82 until they are almost in alignment, which is the case just before the audible indication is produced to indicate the flow of sufficient gas for good ignition.

The audible indication is produced when the valve is turned to the position indicated in Fig. 13, whereat the projections 102 and 116 are shown in alignment. When the projections are substantially in alignment, the disc 82 moves angularly a short distance relative to the disc 110 and the former is moved axially by the spring 79 against the disc 110, thereby to provide the audible indication.

After the indication has been produced, the valve may be moved either to the full on position indicated in Fig. 14 or returned to the low position indicated in Fig. 10. In either case the two discs 82 and 110 move as a unit. Movement beyond the full on position is positively restrained by the radial extension 114 while movement beyond the low position is only impositively restrained.

The valve may be moved to the off position indicated in Fig. 11 from the low position indicated in Fig. 10 upon the application of sufficient turning moment to force the detent disc 110 radially inward and away from the disc 82 by disaligning the projections 102 and 116.

While the particular details of two embodiments of the invention have been described in detail, it should be understood that these are not to be construed as limitative of the invention except in so far as set forth in the accompanying claims.

I claim:

1. A multi-position gas valve of the type including spaced apart stationary stop defining shoulders and a member movable angularly to different positions indicative of the position of the valve, including in combination, a first detent plate mounted on said member and constrained for angular movement therewith, a second detent plate movably mounted in contact with the first plate and movable angularly relative to and with said first plate and member, said second plate having a radial extension having an angular extent less than the distance between said shoulders and movable between and engageable with the shoulders, and means including complementary angularly spaced apart axially extending

frictional driving portions on said plates and axially acting spring means for resiliently urging the two plates into frictional contact with each other so that said second plate is movable with respect to said first plate when said radial extension is disengaged from said shoulders and is movable relative to said first mentioned plate when said extension engages the shoulder.

2. A multi-position gas valve of the type including a pair of angularly spaced apart stationary stop defining shoulders, a member movable angularly to different positions indicative of the position of the valve, including in combination, a first detent plate mounted on said member and constrained for angular movement therewith, a second detent plate movably mounted in frictional contact with the first and movable angularly relative to and with said first plate and member, said second plate having a portion of lesser angular extent than the distance between said shoulder and movable between and engageable with said shoulders and means including complementary angularly spaced apart axially extending frictional driving portions on said first and second plates and spring means resiliently urging the two plates toward each other for drivingly associating said two plates in a slip friction driving relationship.

3. A multi-position gas valve of the type including a member movable angularly to different positions indicative of the position of the valve, including in combination, a first detent plate mounted on said member and constrained for angular movement therewith, a second detent plate movably mounted adjacent the first and movable angularly relative to and with said first plate and member, said first and second plates having contacting frictionally engaged portions whereby the second plate can be driven through the first, a third plate adjacent the second plate on the side opposite the first plate, the detents on said second detent plate projecting in the direction of the third plate to reduce the area of frictional contact therebetween, and means for resiliently urging the plates toward each other to effect a slip friction drive of said second plate through the first.

4. A multi-position gas valve of the type including spaced apart stationary stop defining shoulders and a member movable angularly to different positions indicative of the position of the valve, including in combination, a first detent plate mounted on said member and constrained for angular movement therewith, a second detent plate movably mounted adjacent the first and movable angularly relative to and with said first plate and member and also lengthwise relative to said first plate, said second plate having an extension movable between and engageable with the shoulders, and means for resiliently urging the two plates toward each other, and said first and second detent plates having detents maintaining the two plates in spaced but frictional driving relation when the detents are out of alignment with each other and constraining the two plates for movement together when the detents engage each other, whereby an audible indication is provided when the detents come into substantial alignment upon engagement of the extension with one of the shoulders and subsequent relative movement between the plates whereupon the plates move toward each other.

5. A multi-position gas valve of the type including spaced apart stationary stop defining shoulders and a member movable angularly to

different positions indicative of the position of the valve, including in combination, a first detent plate mounted on said member and constrained for angular movement therewith, a second detent plate movably mounted adjacent the first and movable angularly relative to and with said first plate and member and axially relative to said first plate, said second plate having a radial extension movable between and engageable with the shoulders, a third plate constrained for angular movement with said member and having an angularly narrower radial extension engageable with the shoulders for determining the limit positions of the valve, and spring means for resiliently urging the plates toward each other, said first and second detent plates having equally spaced apart projections maintaining the two plates in spaced but frictional driving relation when the projections are out of alignment with each other and constraining the two plates for movement together when the projections are in nested relation, and said radial extensions being so constructed and arranged with respect to each other and the stops that in one limit position the projections are out of alignment so that when the member moves toward the other limit position, the second plate is moved frictionally with the others until its radial extension engages a stop and the projections move into nested relation and an audible indication is produced, after which all three plates move in unison in either direction and movement in a return direction is positively restrained to indicate an intermediate position of the valve.

6. A multi-position gas valve of the type including spaced apart stationary stop defining shoulders and a member movable angularly to different positions indicative of the position of the valve, including in combination, a first detent plate mounted on said member and constrained for angular movement therewith, a second detent plate movably mounted adjacent the first and movable angularly relative to and with said first plate and member, said second plate having a radial extension movable between and engageable with the shoulders, a third plate constrained for angular movement with said member and having a narrower radial extension engageable with the stops for determining the end positions of the valve, and spring means for resiliently urging the plates toward each other, and said first and second detent plates having equally spaced apart projections maintaining the two plates in spaced but frictional driving relation when the projections are out of alignment with each other for frictional drive of the second plate when said radial extension is out of engagement with the shoulders and for relative movement when said extension engages a shoulder, said projections constraining the two plates for movement together when the projections are in nested relation.

7. A position indicating and determining mechanism for a multi-position gas valve of the type including a valve operating rotatable stem having a flat side and including also a pair of angularly spaced apart stationary stop-defining shoulders, including in combination, a first plate having a flat sided aperture engaging the flat on said stem whereby said plate is constrained to rotate with the stem and having also a radial extension adapted to engage the shoulders and thereby determine the limits of movement of the valve stem, a second plate having a circular stem receiving aperture and mounted upon the valve

stem adjacent the first plate and having a plurality of angularly spaced apart frictional driving portions and having also a radial extension of an arcuate length greater than that of said first mentioned extension but less than the distance between the shoulders, said second plate being both rotatable with and relative to said stem, and a third plate mounted upon the stem adjacent the second having a flat sided central aperture constraining it for movement with the valve stem and a plurality of spaced apart frictional driving portions corresponding to those in the second mentioned plate and extending toward and contacting the second plate, and means including a spring surrounding the stem and bearing against the valve and the first mentioned plate for holding the second plate in slip friction driving relation to the third plate upon the valve stem.

8. A position indicating and determining mechanism for a multi-position gas valve, including a valve operating rotatable stem having a flat side and including also a pair of angularly spaced apart stationary stop-defining shoulders, including in combination, a plate mounted upon the valve stem for rotation with and relative to the stem and having a plurality of spaced apart frictional driving portions and a radial extension of an arcuate length less than the distance between the shoulders, and another plate mounted upon the stem adjacent to and in frictional contact with the second having a flat sided central aperture constraining it for movement with the valve stem and a plurality of spaced apart frictional driving portions corresponding to those in the first mentioned plate, and means for yieldably holding said two plates in slip friction driving relation upon the valve stem.

9. A position indicating and determining mechanism for a multi-position gas valve including a valve operating stem having a flat side and including also a pair of spaced apart stationary stop-defining shoulders, including in combination, a plate mounted upon the valve stem for rotation with and relative to the stem and having a plurality of spaced apart axially extending friction driving portions and a radial extension of an arcuate length less than the distance between the shoulders, and another plate mounted upon the stem adjacent to and in frictional contact with the second having a flat sided central aperture constraining it for movement with the valve stem, a plurality of spaced apart axially extending friction driving portions corresponding to those in the first mentioned plate and a radial extension of lesser arcuate extent than the first mentioned radial extension, and means for yieldably holding said two plates in slip friction driving relation upon the valve stem.
